UNITED STATES PATENT OFFICE.

CHARLES A. HAMMEL, OF LOS ANGELES, CALIFORNIA.

HYDROCARBON-BURNER.

SPECIFICATION forming part of Letters Patent No. 748,862, dated January 5, 1904.

Application filed December 17, 1902. Serial No. 135,598. (No model.)

To all whom it may concern:

Be it known that I, CHARLES A. HAMMEL, a citizen of the United States, residing at Los Angeles, in the county of Los Angeles and State of California, have invented new and useful Improvements in Hydrocarbon-Burners, of which the following is a specification.

My invention relates to that class of hydrocarbon-burners in which oil and steam or compressed air are used as a fuel and are commingled within the burner; and the object is to increase the efficiency and durability of the burner. I accomplish this object by the burner described herein and illustrated in the accompanying drawings, in which—

Figure 1 is a perspective view of my burner complete. Fig. 2 is a perspective view of the burner-tip. Fig. 3 is a central vertical longitudinal section of the burner-tip. Fig. 4 is a front view of the upper rear portion of the tip. Fig. 5 is a view, looking up, of the upper portion of the tip.

In the drawings, A is the steam-supply pipe, which is connected to a suitable supply. (Not shown.) This pipe is screwed into the rear end of steam-chamber B, which chamber is in the lower member or base C of the casting of the burner-tip. The front face of the base is curved and near the front end projects upward and has a slight offset for the reception of the removable wearing-plate D, which plate forms the bottom of the mixing-chamber E. Secured to the base-plate by screw-bolts F, which screw into holes G, is the rear top member H of the tip. In the lower face of this member is the steam-equalizing chamber I, which is in communication with the steam-chamber B through port J. Leading from this equalizing-chamber are three steam-duets K, L, and M. The outer ducts are adapted to discharge the steam on lines that will intersect each other in the mixing-chamber, which chamber is covered by the front top member N, which is secured to the base-plate by bolts O, which screw into holes in the base-plate. These bolts pass through holes in the removable bottom wearing-plate D. The central steam-duct decreases in depth from the equalizing to the mixing-chamber, but is of the same width, its outlet being wide and flat. The object of this construction is for the purpose of having the full

equalizing strength of the steam from the equalizing-chamber to break up and force the oil through the intersection of the steam-pressure from the side steam-duets. In the front top member is a recess broad and narrow at the front and decreasing in width, but increasing in depth, the side lines of which terminate on each side of the steam-duets and nearly on a line with the top thereof. In each edge of the top portion of this recess is a channel 10 for the reception of the edge of the removable upper removable wearing-plate R, which is held against accidental displacement by the set-screw S. The oil-pipe T, connected to a suitable supply, (not shown,) screws into an oil-chamber U, which chamber is connected by oil-duct V with the mixing-chamber. This oil-duct terminates between the side steam-duets and over the central steam-duct, as shown most clearly in Fig. 4. A steam by-pass W connects the oil and steam pipes, so that, if desired, the oil-passages may be cleaned out with steam.

It will be observed that the general form of the burner-tip is very similar to Patent No. 640,378, issued to me on January 2, 1900; but in that patent there is a direct straight passage through the equalizing-chamber into the mixing-chamber, and the steam-duct under the oil-duct is of uniform size from equalizing-chamber to the mixing-chamber, which caused a loss of steam-pressure of the steam passing through this duct by reason of the friction on the sides of the ducts and also caused undue wear on the walls of the duct, which soon threw the ducts out of balance, thereby producing an uneven flame. The duct was also substantially square in cross-section. There were no removable plates to form the top and bottom surfaces of the mixing-chamber. I found in practice that the direct straight passage of the steam through the equalizing-chamber and into the mixing-chamber was detrimental to the efficiency of the burner. I also found that the top and bottom surfaces of the mixing-chamber would be cut by the action of the steam and the impurities of the oil and that as soon as these surfaces were cut the flame was uneven and the tip must be removed and replaced by a new one. By using removable plates when these surfaces become cut the plates can be

removed and replaced by new ones at a very slight expense and the remaining parts of the tip may be utilized for further use, they being as good as new.

5 Having described my invention, what I claim as new, and desire to secure by Letters Patent, is—

1. A hydrocarbon - burner comprising a steam-chamber below an equalizing-chamber 10 and connected therewith; an oil - chamber above the equalizing - chamber; a mixing-chamber in front of said equalizing-chamber; three ducts leading from said equalizing-chamber into said mixing-chamber, the outer 15 ducts being adapted to discharge steam in planes which meet in said mixing-chamber, and the central duct being wide and shallow at the front and deeper at the rear thereof; an oil - duct terminating between the side 20 steam-ducts and above the central steam-duct and connecting said oil - chamber with said mixing-chamber.

2. An atomizer formed of members fitted together, and having a chamber and an outlet-cavity between them, and means for atomizing and directing liquid from the outlet, and detachable wearing - plates lining the walls of the outlet-cavity to guide the material to be discharged.

3. An atomizer having an outlet - cavity 30 grooved in each corner, and removable wearing-plates in said grooves.

4. An atomizer having removable flat wearing-plates forming the walls of its outlet.

5. In a hydrocarbon-burner having a cavity 35 leading to the discharge-orifice of the burner-tip, a removable wearing - plate in the top thereof.

6. In a hydrocarbon-burner having a cavity leading to the discharge-orifice of the burner- 40 tip, a removable wearing-plate in the bottom thereof, extending from end to end of the cavity and fixedly held and receiving upon its longitudinal surface the direct impact of the vapors.

7. A hydrocarbon-burner having a cavity leading to the discharge-orifice of the burner- 45 tip, and removable wearing-plates in the top and bottom thereof said plates forming the wearing-surfaces of the top and bottom of 50 said cavity.

In witness that I claim the foregoing I have hereunto subscribed my name this 10th day of December, 1902.

CHARLES A. HAMMEL.
